(57) **CLAIM**

The ornamental design for a seat belt lift latch, as shown and described.

DESCRIPTION

FIG. 1 is a perspective view of a seat belt lift latch showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another perspective view thereof; and,

FIG. 9 is a perspective view thereof showing the seat belt lift latch in a position of use.

The broken lines shown in FIG. 9 are for the purpose of illustrating environment and form no part of the claimed design.
